UNITED STATES PATENT OFFICE.

FRIEDRICH WILHELM WITTE, OF LEIPZIG-PLAGWITZ, GERMANY, ASSIGNOR TO
DEUTSCHE KUGELLAGERFABRIK G. M. B. H., OF LEIPZIG-PLAGWITZ, GERMANY.

SHAFT-SUPPORT.

1,136,637.

Specification of Letters Patent.

Patented Apr. 20, 1915.

Application filed March 18, 1911. Serial No. 615,211.

To all whom it may concern:

Be it known that I, FRIEDRICH WILHELM WITTE, a citizen of the United States of America, residing at Leipzig-Plagwitz, in 5 the Empire of Germany, have invented a new and useful Shaft-Support, of which the following is a specification.

Ball-bearings comprising an outer stationary race-ring and an inner rotary race- 10 ring are very sensitive even to slight irregularities in the mounting and to deformations, whereby their employment in shaftings under such circumstances is rendered very difficult.

15 My invention relates to means for so positioning and adjusting ball-bearings in hangers, plummer-blocks and other shaft-supports, that all secondary strains produced by the said irregularities and deformations and likely to result in premature destruction of the ball-bearing are avoided. The said means permit one to vertically and 20 horizontally adjust the ball-bearing while leaving its outer stationary race-ring at liberty to slight shift and follow the varying bending of the shaft under the action 25 of its load or strain. According to the circumstances either all or a part of the said means may be employed at a time, as may 30 be required.

I will now proceed to describe my invention with reference to the accompanying drawings, in which—

Figure 1 is an elevation of a hanger provided with means for vertically and horizontally adjusting a ball-bearing, parts being shown in section. Fig. 2 is a side view of the same, Fig. 3 is a section through the ball-bearing on the line A—B in Fig. 1 and 35 shows a part of the shaft in elevation, Fig. 4 is a similar section through the line B—C in Fig. 1, Fig. 5 is a section through the line D—E in Fig. 2, Fig. 6 is similar to Fig. 4 and shows a modification, Fig. 7 is an elevation of a part of a modified 40 hanger with other means for vertically adjusting and horizontally securing a ball-bearing, Fig. 7^a is a vertical section through the line F—G in Fig. 7, Fig. 8 is a side view of the opposite part of the hanger in Fig. 7, Fig. 9 is an elevation of the greatest 45 part of a plummer-block provided only with means for horizontally adjusting a ball-bearing, Fig. 10 is a horizontal sec- 50 tion through the line H—J in Fig. 9, and Fig. 11 is a vertical section through the part c shown in Fig. 9.

Similar letters of reference refer to similar parts throughout the several views.

Figs. 1 to 5 illustrate a hanger suitable 60 for a ball-bearing. The hanger h has an enlarged lower portion h¹ shown in section in Fig. 5 and a large central hole p for the ball-bearing and two lateral cross holes q housing each a box d. The ball-bearing 65 may be of any known construction and comprises an outer stationary race-ring a, which is shown to have a spherical outside and to have therein two opposite recesses b b. Each recess has two horizontal faces b¹ and 70 b² and a curved bottom b³ which forms a part of a cylindrical surface, the vertical axis of which passes through the axis of the ball-bearing, as can be best seen from Fig. 4. The hanger h is provided with four 75 adjusting screws g g which are disposed in parallel pairs in the same central cross plane and on both sides of the large central hole p, the two screws g g in each pair being in the same axis and opposite to one 80 another. Their reduced ends g¹ g¹ have concave end faces which face one another. Between them a box d can be introduced into the cross hole q, which box has in its vertical side d¹ a threaded hole for a horizontal 85 adjusting screw e, which can be secured by means of a nut f. In its upper and lower surfaces the box d has a recess d² larger in diameter than the reduced end g¹ of any adjusting screw g. The bottom d³ of each recess d² forms a part of a globular surface, the center of which is the point of intersection of the horizontal axis of the adjusting screw e and of the vertical axis of the two screws g g. The concave end faces of the 90 reduced ends g¹ g¹ of the upper and lower adjusting screws g g can press on the spherical bottoms d³ d³ of the recesses d² d² of the boxes d and it will be understood, that in this manner the center of the box d can 95 be guided in the common axis of the two screws g g on the latter being vertically adjusted. After adjustment the two screws g g can be secured by means of nuts g² g². Each box d has a horizontal bore in the 100 axis of the screw e, in which bore the cylindrical pivot c² of a guide c (Fig. 4) is 105 rotatably mounted. The guide c has a rec-

tangular part c^1 , which is adapted to engage in one of the two recesses b in the outer race-ring a . This part c^1 has a plane face which is adapted to come in contact with the cylindrical bottom b^3 of the recess b and may be lined with some metal, as is indicated by dotted lines in Fig. 4. At the sides the rectangular part c^1 is provided with ledges c^3 , which project over the outer race-ring a , a slight play being left between them. In this manner the outer race-ring a of the ball-bearing is held in position between the two opposite guides c in the horizontal plane. In consequence of the construction described the rectangular part c^1 is as high as the pivot c^2 , but longer than the width of the race-ring a . The inner end face of the adjusting screw e can bear against the end face c^4 of the pivot c^2 and as the latter may be longitudinally shifted in the box d , it is evident, that the center of the ball-bearing can be horizontally adjusted, and also vertically by means of the adjusting screws g g . It is very easy for the fitter to accurately adjust the two boxes d and the two guides c , before he introduces the shaft r with the ball-bearing. When the shaft r bends under the action of its load or strain in the vertical plane, the outer race-ring a can turn with the two guides c , since the pivots c^2 of the latter are permitted to turn in the two boxes d . When the shaft r bends in the horizontal plane, this is permitted by the outer race-ring a sliding along the two plane surfaces of the rectangular parts c^1 of the guides c in opposite directions. When the shaft contracts or expands in consequence of the variations of the temperature a like compensation will take place in the same locations, but on both sides in the same sense. In this manner the ball-bearing will be permitted to slightly shift in any direction and follow any bending of the shaft r , so that all secondary strains upon the ball-bearing are avoided and consequently the latter is protected from premature destruction. When the outer stationary race-ring a of the ball-bearing shows traces of wear on the loaded side, it is possible to turn the ball-bearing through an angle of 180° , either around the shaft or about its vertical axis and to use its unused side.

Fig. 6 illustrates a modification, in which the bottom b^3 of each recess b in the outer race-ring a is made plane and parallel to the axis of the shaft r , while the surface c^5 in contact therewith of the guide c forms a part of a cylindrical surface. This simple construction is a little cheaper than that hereinbefore described and certainly answers for longitudinal contractions and expansions of the shaft, but is not so good for bendings of the shaft in the horizontal plane. It can be recommended only in case

the forces acting in the said plane are small in proportion to the strain to which the shaft is subjected.

In cases where the adjustability of the ball-bearing in the horizontal plane is of no importance, the means described for positioning and adjusting the ball-bearing may be simplified in a manner illustrated at Figs. 7 to 8. Here the outer race-ring a is turned through an angle of 90° , so that its two recesses b and the two guides c are on a vertical axis. The pivot c^2 of each guide c may be mounted to rock in the bore of a vertical adjusting screw i provided in the upper part k^1 and lower part k^2 respectively of the hanger k .

In heavy constructions the vertical part k^3 of the hanger may be provided with a vertical slot k^4 in the horizontal plane of the shaft, in which slot a stop-screw l can be adjusted by means of nuts m for taking up the thrust of the shaft. The stop-screw l can be made to exactly touch the outside of the outer race-ring a and can be vertically adjusted in the slot k^4 so as to be exactly in the horizontal plane of the ball-bearing. If the hanger is closed, that is made integral on both sides with the lower part k^2 , of course a similar stop-screw may be disposed on the opposite side, so that the strain in either direction can be taken up.

In order that the stop screw l will not prevent the shaft from bending and the ball-bearing from turning around the pivots c^2 , it is preferable to form the portion of the ring a likely to come in contact with the contact-screw l as a part of a solid of revolution, the axis of which coincides with that of the two adjusting screws i .

In other cases, such as for example for countershafts or shafts supported only on two or three points, it will suffice to adjust the ball-bearing only transversely. Then the arrangement illustrated at Figs. 9 to 11 for a plummer-block may be employed. Here the outer race-ring a^1 is made globular on its outside and is inserted in a shell a^2 having a globular outside and inside. This shell a^2 has in its globular outside two opposite recesses b as described above with reference to Fig. 1. In these recesses two guides c are made to engage, which are similar to those described above with reference to Figs. 1 and 2, only that they have each a central bore c^6 (Fig. 11) and no pivot. In this central bore c^6 the reduced cylindrical end n^1 of a horizontal adjusting screw n can engage, which latter engages in female thread in one of the two eyes o^1 of the plummer-block o and can be therein secured by means of a nut n^2 .

The means just described for positioning and adjusting a ball-bearing can of course be applied to a hanger, the ball-bearing with the guides c being again turned

through an angle of 90° as described above with reference to Fig. 7.

I claim:

1. In a shaft support, an automatically adjustable ball-bearing comprising an inner rotary race-ring, an outer stationary race-ring having opposite recesses diametrically located, guides having each an extension reaching into the corresponding recess, said recesses being wider than the guides to allow an axial shifting of the bearing and having rounded bottoms to allow a movement around a line crossing the axis of the bearing, and a swinging pivot for each guide connecting the guide with the shaft support.
2. In a shaft support, an automatically adjustable ball-bearing comprising an inner rotary race-ring, an outer stationary race-ring having two opposite recesses diametrically located, two guides having each an extension reaching into the corresponding recess, said recesses being wider than the guides to allow an axial shifting of the bearing and having rounded bottoms to allow a movement around a line crossing the axis of the bearing, and a cylindrical pivot for each guide establishing connection with the shaft support.
3. In a shaft-support, the combination with a ball-bearing for a shaft comprising an inner rotary race-ring, an outer stationary race-ring spherical on the outside and balls between them, of means for adjusting the ball bearing, and means for allowing said outer spherical race-ring to slightly shift under the strain of the load comprising

ing, a support, two opposite adjusting screws in the same axis in said support, the outer race-ring having in its outside portion two opposite recesses with sides in 40 two parallel planes equidistant from the axis of the shaft and with rounded bottoms at right angles to these two planes, the vertical axis of said rounded bottoms cutting the axis of the shaft, and two guides with 45 parallel side surfaces revolubly connected with said two adjusting screws and adapted to engage with their plane side surfaces in the two recesses of said outer race-ring.

4. In a shaft-support, the combination 50 with a ball-bearing for a shaft comprising an inner rotary race-ring, an outer stationary race-ring spherical on the outside and balls between them, of a shell encircling the outer race-ring of said ball-bearing and having a spherical outer surface with two opposite recesses which have side surfaces in two parallel planes equidistant from the axis of the shaft and rounded bottoms at right 55 angles to these two planes, the vertical axis of said rounded bottoms cutting the axis of the shaft, a support, two opposite adjusting screws on the same axis in said support, and two guides with parallel side surfaces revolubly connected with said two adjusting 60 screws and adapted to engage their side surfaces in the two recesses of said shell.
